B. M. FINE,
THERMOSTATIC SWITCH.
APPLICATION FILED DEC. 18, 1919.

1,407,020.

Patented Feb. 21, 1922.

Inventor
Bernard M. Fine
By his Attorney
E. W. Marshall

UNITED STATES PATENT OFFICE.

BERNARD M. FINE, OF EAST ORANGE, NEW JERSEY, ASSIGNOR TO WILFORD J. HAWKINS, OF MONTCLAIR, NEW JERSEY.

THERMOSTATIC SWITCH.

1,407,020.

Specification of Letters Patent. Patented Feb. 21, 1922.

Application filed December 18, 1919. Serial No. 315,732.

To all whom it may concern:

Be it known that I, BERNARD M. FINE, a citizen of the United States of America, and a resident of East Orange, Essex County, 5 and State of New Jersey, have invented certain new and useful Improvements in Thermostatic Switches, of which the following is a specification, reference being had to the accompanying drawings, forming a part 10 thereof.

This invention relates to improvements in that type of switches in which an electric switch is actuated automatically by changes in temperature. Its object is to provide a 15 compact and inexpensive structure which is efficient in operation. Another object is to provide a device of this character which is so constructed and arranged as to use as a part thereof an ordinary snap switch of 20 commercial form. Another object is to provide a simple and easily manipulated arrangement for adjusting or setting the thermostat to actuate the switch at predetermined temperatures.

25 These and other objects of the invention will appear in the following specification in which I will describe the invention, the novel features of which will be set forth in appended claims.

30 Referring to the drawings:

Figure 1 is a central sectional elevation of a thermostatic switch which is made according to and embodies this invention.

Figure 2 is a sectional plan view of the 35 same device, the section being taken on the line 2—2 of Figure 1.

Figure 3 is a fragmentary sectional elevation illustrating another operative position of the parts with the switch closed.

40 Like characters of reference designate corresponding parts in all the figures of the drawings.

10 designates a cylindrical cup-like metallic casing flanged at the top as at 11. A 45 cover 12 which supports all the other parts of the device is secured to this flange by bolts 13. A cup shaped expandible metallic bellows 14 has a flange at its upper edge which is soldered or brazed to a ring 15 50 which in turn is soldered or brazed to the under side of the cover. The lower or closed end of the expandible metallic bellows is designated at 16.

20 is a flat circular plate from which guide 55 rods 21 extend up into and through the

cover. This plate is secured to the end 16 of the expandible metallic bellows by studs 22 which have collars 23 and are threaded at their lower ends to receive nuts 24. In the cover 12 are external threaded guide 60 bushings 25 for the guide rods 21, the lower ends of which bushings abut against compression springs 26. The other ends of these springs press the plate 20 downwardly.

30 is an electric snap switch which may be 65 of any of the well-known commercial forms. It is secured to the cover 12 by a bracket 31. The particular switch shown, has a transverse plunger the ends of which are designated by 32, 33, which has a lost motion connection with a switch arm 34 adapted to be moved by the plunger into and out of contact with terminal contacts 35, 36 with which conductors 37 and 38 are connected.

The end 32 of the plunger rests upon or is 75 in close proximity to the plate 20 toward which it is pressed by a spring 27 in a closed cap 28 threaded into the central part of the cover 12.

80 The operation of this apparatus is as follows: The part of the casing 10 outside of the expandible metallic bellows is filled with a fluid which is sensitive to temperature changes, such for example, as sulphur dioxide, which has a high coefficient of expansion. The springs 26 force the plate 20 downwardly and its movement in this direction is limited by the contact of the lower ends of the studs 22 with the casing 10. When in this position the switch plunger is 90 free to move under the influence of spring 27 to actuate the switch arm 34 in the desired direction. In the particular arrangement shown, the switch arm is actuated to open the switch when the parts are in the 95 positions in which they are shown in Figure 1.

100 The increase of temperature will cause an increase of pressure on the closed end of the expandible metallic bellows which will tend to raise it and the plate 20. The springs 26 are adjusted to permit the plate 20 to be raised at a desired temperature. In rising, the plate 20 will push the switch plug upwardly against the spring 27 to actuate the 105 switch arm in the opposite direction, or as shown in Figure 3 to close the switch. The upward movement of the expandible metallic bellows is limited by the upper ends of studs 22 coming in contact with the cover 12.

It is obvious that the operation as just described is reversed when the temperature decreases. In such a case the springs 26 will force the plate 20 downwardly until the 5 plunger is free to be actuated by the spring 27.

Various modifications of structure may be made within the spirit and scope of this invention, and I intend no limitations other 10 than those imposed by the appended claims.

What I claim is:

1. A thermostatic switch comprising a cover, an expansible metallic bellows having a closed end and an open end with its open 15 end affixed to the cover, a casing surrounding but spaced from the expansible metallic bellows forming a closed chamber outside of the expansible metallic bellows, a contact making device mounted within the expansible metallic bellows, and means within the expansible metallic bellows for actuating the contact making device.

2. A thermostatic switch comprising a cover, an expansible metallic bellows having a closed end and an open end with its open 25 end affixed to the cover, a casing surrounding but spaced from the expansible metallic bellows forming a closed chamber outside of the expansible metallic bellows, a plate 30 secured to the closed end of the expansible metallic bellows, a contact making device mounted on the cover within the expansible metallic bellows and means controlled by the movement of the plate for actuating the 35 contact making device.

3. A thermostatic switch comprising a cover, an expansible metallic bellows having a closed end and an open end with its open 40 end affixed to the cover, a casing surrounding but spaced from the expansible metallic bellows forming a closed chamber outside of the expansible metallic bellows, a plate on 45 the closed end of the expansible metallic bellows, studs securing the plate to the expansible metallic bellows and arranged to limit the movement thereof, a contact making device mounted on the cover within the expansible metallic bellows, and means controlled by the movement of the plate for 50 actuating the contact making device.

4. A thermostatic switch comprising a cover, an expansible metallic bellows having a closed end and an open end with its open 55 end affixed to the cover, a casing surrounding but spaced from the expansible metallic bellows forming a closed chamber outside of the expansible metallic bellows, a plate on the closed end of the expansible metallic bellows, studs securing the plate to the expansible metallic bellows and arranged to limit the movement thereof, guide rods projecting from the plate into the cover, a contact 60 making device mounted on the cover within the expansible metallic bellows, and means controlled by the movement of the plate for actuating the contact making device.

plate for actuating the contact making device.

5. A thermostatic switch comprising a cover, an expansible metallic bellows having a closed end and an open end with its open 70 end affixed to the cover, a casing surrounding but spaced from the expansible metallic bellows forming a closed chamber outside of the expansible metallic bellows, a plate on the closed end of the expansible metallic bellows, studs securing the plate to the expansible metallic bellows and arranged to limit the movement thereof, guide rods projecting from the plate into the cover, springs surrounding the guide rods and arranged to 75 push the plate and the closed end of the expansible metallic bellows away from the cover, a contact making device mounted on the cover within the expansible metallic bellows, and means controlled by the movement 80 of the plate for actuating the contact making device.

6. A thermostatic switch comprising a cover, an expansible metallic bellows having a closed end and an open end with its open 85 end affixed to the cover, a casing surrounding but spaced from the expansible metallic bellows forming a closed chamber outside of the expansible metallic bellows, a plate on the closed end of the expansible metallic bellows, studs securing the plate to the expansible metallic bellows and arranged to limit the movement thereof, guide rods projecting from the plate into the cover, externally threaded guide bushings for said 90 100 guide rods in the cover, springs surrounding the guide rods abutting against said bushings and arranged to push the plate and the closed end of the expansible metallic bellows away from the cover, a contact making device mounted on the cover within the expansible metallic bellows, and means controlled by the movement of the plate for 105 actuating the contact making device.

7. A thermostatic switch comprising a 110 cover, an expansible metallic bellows having a closed end and an open end with its open end affixed to the cover, a casing surrounding but spaced from the expansible metallic bellows forming a closed chamber outside 115 of the expansible metallic bellows, a plate secured to the closed end of the expansible metallic bellows, a switch mounted on the cover within the expansible metallic bellows comprising a member for actuating said 120 switch, and resilient means on the cover for moving the actuating member in one direction, said plate being arranged to move said member in the opposite direction.

8. A thermostatic switch comprising a 125 cover, an expansible metallic bellows having a closed end and an open end with its open end affixed to the cover, a casing surrounding but spaced from the expansible metallic bellows forming a closed chamber outside 130

of the expansible metallic bellows, a plate on the closed end of the expansible metallic bellows, studs securing the plate to the expansible metallic bellows and arranged to 5 limit the movement thereof, guide rods projecting from the plate into the cover, a switch mounted on the cover within the expansible metallic bellows comprising an actuating member for actuating said switch, 10 and adjustable resilient means on the cover for moving the actuating member in one direction, said plate being arranged to move said member in the opposite direction.

9. A thermostatic switch comprising a 15 cover, an expansible metallic bellows having a closed end and an open end with its open end affixed to the cover, a casing surrounding but spaced from the expansible metallic bellows forming a closed chamber outside 20 of the expansible metallic bellows, a plate on the closed end of the expansible metallic bellows, studs securing the plate to the ex-

pansible metallic bellows and arranged to limit the movement thereof, guide rods projecting from the plate into the cover, externally threaded guide bushings for said guide rods in the cover, springs surrounding the guide rods abutting against said bushings and arranged to push the plate and the closed end of the expansible metallic 25 bellows away from the cover, a switch mounted on the cover within the expansible metallic bellows comprising a member for actuating said switch, an adjusting member threaded through the cover, and a 30 spring between said adjusting member and the switch actuating member arranged to move the actuating member in one direction, said plate being arranged to move said actuating member in the opposite direction 35 against the action of said spring.

In witness whereof, I have hereunto set my hand this 15th day of December, 1919.

BERNARO M. FINE.
